INVENTOR

Louis T. Cassidy

BY

James J. Healy & Co., ATTORNEYS

UNITED STATES PATENT OFFICE.

LOUIS T. CASSIDY, OF NORWICH, CONNECTICUT.

SURGICAL APPLIANCE.

Application filed January 14, 1920. Serial No. 351,397.

To all whom it may concern:

Be it known that I, LOUIS T. CASSIDY, a citizen of the United States, residing at Norwich, in the county of New London and State of Connecticut, have invented new and useful Improvements in Surgical Appliances, of which the following is a specification.

My present invention pertains to surgical appliances and it contemplates the provision of a device whereby any portion of the liquid contained in a vacuum vessel, such for instance, the well known "thermos" bottle, may be removed without lowering the temperature of the contents remaining in the vessel.

My novel appliance is highly efficient when used for and in connection with inter-venous injections, the Murphy drip method or the Dakin Carroll solution, and where an irrigator is used it being especially advantageous to maintain the solution at a high and even temperature during said injections.

In order that those skilled in the art will be fully aware of the advantages of my novel device, I deem it well to state that heretofore it has been the custom to place the heated solution into an irrigator, in which the solution quickly cools and it is very difficult to keep the solution at an even temperature while in use, which is an absolute necessity.

Experience has demonstrated that this cooling of the solution has on many occasions been attended with disastrous results and it is the purpose of my novel device to overcome such disadvantages.

The invention in all of its details will be fully understood from the following description and claim when the same is read in connection with the drawings, accompanying and forming part of this specification, in which:

Figure 1 is a side elevation showing my novel appliance arranged on the well-known "thermos" or vacuum bottle.

Figure 2 is a sectional view of Figure 1. Similar numerals of reference designate corresponding parts in all of the views of the drawings.

In order to more readily disclose my invention, I have illustrated the same as applied to a "thermos" bottle of the ordinary

construction as indicated by 1 and having 55 the cap 2, inner bottle 3, washer 4, and the cork or stopper 5. The bottle forms no part of my invention and in this connection I would have it distinctly understood that my invention is applied to any form of 60 vacuum vessel or pan.

As illustrated by Figure 2, I drill or otherwise cut, the longitudinal openings through the cork or stopper 5 and in the upper end of the cap 2, I provide openings that register with those of the cork. 65

Into the openings in the cork and cap and thence into the slots 6, I insert my novel glass tubes 7 and 8.

The tube 7 is for the admission of air so 70 as to permit the fluid to freely flow from the container. This tube 7 is provided with the outwardly directed portion 7' and the downwardly directed portion 9 of the end of which, when deemed necessary, a cap 10 of 75 rubber or other material may be placed.

The cap 10 is employed to prevent the possibility of air entering the bottle. However, experience has demonstrated that because of its construction, the tube 7 will 80 preclude entry into the container of air when said container is standing in the position illustrated by the drawings.

The tube 8 is inserted into the remaining opening 6 of the cap and at its outer end 85 11 said tube may be crimped to receive a hose or other conduit 12.

In the practical use of the appliance during a venous or other injection, the cap 10 is removed from the portion 9 of tube 7 90 and the bottle tilted so that the cap 2 is placed in a downward position. Liquid will readily flow from the bottle through tube 8 and thence through conduit 12, where it may be injected into a patient. 95

It will be readily apparent that when the container is returned to its proper position, cooling of the liquid will be precluded.

Moreover, the necessity for removing the cap 2 and cork 5 is dispensed with and therefore the liability of a nurse or other attendant becoming so engrossed in the work that they will overlook returning the cap and cork to the proper places is effectually precluded. 105

Because of the fact that air enters the bottle or container only during the actual use of the solution, and this being in such

an infinitesimal degree liability of the solution becoming chilled to a dangerous degree is precluded.

I would distinctly have it understood that the openings 6 of the cork or stopper 5 are of such size as to snugly grip the tubes 7 and 8, and hence not only will air be prevented from contacting with the solution by passing between the openings 6 and outer surfaces of the tubes 7 and 8, but during the tilting of the container, the tubes will be prevented from being displaced from the cork and thus broken by striking the floor or other surface.

Having described my invention, what I claim and desire to secure by Letters-Patent, is:

In a surgical appliance, the combination of a vacuum vessel, a closure for said vessel, a cap secured on the vessel and having apertures therein, two channels formed in said closure and extending the full length thereof and adapted to communicate with the apertures of the cap and atmosphere, a

tube snugly held in one channel of the closure whereby the contents of the vessel may pass when desired from said vessel and a second tube snugly held in the other channel, each of the tubes being separated from the walls of the cap; said last named tube having an outwardly reaching upper end that terminates in a downwardly reaching portion that extends at an angle to the portion of the tube held in the closure whereby when the vessel is standing in its upright position the effect of atmosphere on the temperature of the contents of said vessel will be extremely slow and when the vessel is tilted the contents will flow from the first named tube.

In testimony whereof I have hereunto set my hand in presence of two subscribing witnesses.

LOUIS T. CASSIDY.
